[57] CLAIM

The ornamental design for a hot air supply type electric oven, as shown and described.

DESCRIPTION

FIG. 1 is a front elevation of a hot air supply type electric oven showing my new design;
FIG. 2 is a rear elevation thereof;
FIG. 3 is a plan view thereof;
FIG. 4 is a bottom view thereof;
FIG. 5 is a right side view thereof;
FIG. 6 is a left side view thereof; and
FIG. 7 is a perspective view of an oven showing my new design, where the base and the outer case to be mounted thereon are separated one from the other.
